UNITED STATES PATENT OFFICE.

GEORGE SHATSWELL, OF WAUKEGAN, ILLINOIS.

DESIGN FOR WINDOW-SCREEN.

Specification forming part of Design No. 7,870, dated November 17, 1874; application filed October 13, 1874.
[Term of Patent 7 years.]

To all whom it may concern:

Be it known that I, GEORGE SHATSWELL, of Waukegan, in the county of Lake and State of Illinois, have invented a new Design for Door and Window Screens, of which the following is a description:

The nature of this design will be readily understood by referring to the annexed photographic illustration.

A represents the frames of the screen, and B the line on which they may swing. The frames are of dark color on their inner and outer margins Z X, and between these margins

are lighter colored stripes C. The lifting-braces H have serpentine forms, which, together with the striped frames, give the screen a very neat appearance.

I claim—

A design for screens for doors and windows, consisting of the dark margins Z X, stripes C, and serpentine lifting-braces H, as shown.

GEORGE SHATSWELL.
